Primary Examiner — Cynthia Ramirez*Assistant Examiner* — Gino Colan(74) *Attorney, Agent, or Firm* — Dorsey & Whitney LLP(57) **CLAIM**The ornamental design for an asymmetrically-shaped bottle,
as shown and described.**DESCRIPTION**

FIG. 1 is a front, left isometric view of an asymmetrically-shaped bottle.

FIG. 2 is a front elevation view of the asymmetrically-shaped bottle of FIG. 1.

FIG. 3 is a rear elevation view of the asymmetrically-shaped bottle of FIG. 1.

FIG. 4 is a right side elevation view of the asymmetrically-shaped bottle of FIG. 1.

FIG. 5 is a left side elevation view of the asymmetrically-shaped bottle of FIG. 1; and,

FIG. 6 is a top plan view of the asymmetrically-shaped bottle of FIG. 1.

The broken lines shown in the figures are included for the
purpose of illustrating portions of the asymmetrically-shaped
bottle and form no part of the claimed design.**1 Claim, 5 Drawing Sheets**| References Cited		EM	001753591-0001	1/2011
